COTTON CLEANING MACHINE

John T. Lawrence, Inman, S. C.

Application April 11, 1940, Serial No. 329,157

9 Claims.

(Cl. 19—76)

This invention relates to an improved construction of machine adapted to be attached to the suction or inlet end of a cotton gin or mill for cleaning the cotton before it is admitted to the gin or mill.

More particularly, it is an object of this invention to provide a cotton cleaning machine through which cotton is conveyed by suction from a gin or mill to which the machine is attached and having means for breaking up the cotton bolls and lint for separating the foreign matter therefrom including two cleaning stages whereby fine particles of foreign matter and larger particles of foreign matter may be separately separated from the cotton during the cleaning operation thereof.

Still another aim of the invention is to provide a machine so constructed that a portion of the cotton passing therethrough and from which the foreign matter has been removed may be drawn directly through a separate conduit of the machine to the gin or cotton mill without being subjected to all of the cleaning operations provided in the machine.

Still another aim of the invention is to provide a sieve of mesh wire fabric disposed adjacent a revolving beater and so constructed and reinforced that the screen will form a corrugated surface for co-acting with the beater in breaking up the cotton bolls and lint to separate the foreign matter therefrom and to also act as a sieve through which the fine particles of foreign matter may pass and be thereby separated from the cotton.

Still another aim of the invention is to provide an improved construction of conveyor belt for the cotton and heavier particles of foreign matter having means for holding the foreign matter so that the cotton may be readily removed, separately, from the belt.

Other objects and advantages of the invention will hereinafter become more fully apparent from the following description of the drawings, which illustrate a preferred embodiment thereof, and wherein:

Figure 1 is a side elevational view of the machine,

Figure 2 is an end view in elevation of the same looking toward the outlet end thereof,

Figure 3 is a longitudinal, vertical sectional view taken substantially along the plane of the line 3—3 of Figure 2,

Figure 4 is a longitudinal, horizontal sectional view taken substantially along the plane of the line 4—4 of Figure 3,

Figure 5 is a similar view taken substantially along the plane of the line 5—5 of Figure 3,

Figure 6 is a transverse, vertical sectional view taken substantially along the plane of the line 6—6 of Figure 3,

Figure 7 is a longitudinal, horizontal sectional view taken substantially along the plane of the line 7—7 of Figure 3, and

Figure 8 is a fragmentary, side elevational view, partly in section, on an enlarged scale, of a portion of the side of the machine seen in Figure 1.

Referring more particularly to the drawings, wherein like reference characters designate like or corresponding parts throughout the different views, 10 designates generally a cotton cleaning machine which includes a casing 11 having an inlet end or conduit 12 and an outlet end or conduit 13. Bars 14 are secured to the casing 11, adjacent its ends, and are provided with spaced apertures by means of which the bars 14 are adapted to be connected to a supporting frame or other means, not shown, for mounting the machine 10. The casing 11 includes the top and bottom sections 15 and 16 which are detachably connected to one another by means of angle members 17 which are carried by the sections 15 and 16 and which are detachably secured together by means of the nut and bolt fastenings 18. The upper section 15 is provided with the reinforced edges 19 and with reinforcing bars 20, disposed on opposite sides thereof.

Referring particularly to Figure 3, the upper section 15 is provided with a horizontal longitudinally disposed partition 21 which extends from side to side thereof and from adjacent the inlet end 12 to adjacent the outlet end 13. The partition 21 is disposed substantially parallel to the sloping top of the casing 11 to form a passage 22 and is provided, intermediate of its ends, with an opening 23 for connecting the passage 22 to the interior of the casing 11. A valve or damper 24 is slidably mounted on the partition 21 for closing the opening 23 and is provided with a rack bar 25 for meshing with a pinion 26 keyed to a shaft 27 which extends through the side walls of the casing 11 and which is journaled therein. Shaft 27 may be revolved in any suitable manner, not shown, for closing or opening the valve or damper 24.

Between the inlet passage 12 and the adjacent end of the passage 22 a mesh wire fabric drum 28 is disposed. Drum 28 is mounted on a shaft 29 which is journaled in the sides of the casing 11 for rotatably mounting the drum 28. The portion of the top of the casing 11 directly above the drum 28 is bowed outwardly at 30 to accommodate the drum. As best seen in Figure 3, the inlet passage 12 is pivotally mounted so that it can be swung from a horizontal position, as seen in full lines, to a vertical position, as seen in dotted lines, for directing cotton which is adapted to enter the casing therethrough either toward the drum 28 or downwardly of the casing 11. A revolving beater, designated generally 31 is mount-

ed in the section 15 beneath the drum 28 and includes a hub 32 which is keyed to a shaft 33 which is journaled in the sides of the casing 11. A plurality of spikes or tines 34 are secured in and extend radially from the hub 32 to complete the beater 31. The length of the tines or spikes 34 are substantially the same so that their free ends are each disposed substantially the same distance from the shaft 33 and combine to form the periphery of the beater 31. A corrugated arcuately shaped plate 35 is secured at one end by means of the fastenings 36 to an end wall of the casing 11. The baffle 35 is disposed adjacent a portion of the periphery of the beater 31 and its surface is serrated so that it forms a plurality of undulations which extend transversely of the casing 11. A shaft 37 extends transversely through the casing 11 for supporting a plurality of slats 38, which are longitudinally disposed relatively to the casing in spaced apart relationship relatively to each other. The slats 38 have corresponding ends 39 which are bent to engage loosely around the shaft 37. Slats 38 are connected to each other by means of a plurality of spaced transversely disposed slats 40 which are mounted on the upper sides of the slats 38. A strip of mesh wire fabric 41 is disposed over the slats 38 and 40 and connected in any suitable manner, not shown, to the slats 38 between the slats 40 to arrange the screen so that its surface of undulating formation will be similar to the baffle 35. As best seen in Figure 3, the opposite free end of the baffle 35 rests on the end of the fabric 41 which is disposed over the ends 39 of the slats 38. Slats 38, slats 40 and the screen fabric 41 combine to form a screen or sieve, designated generally 42 which forms a continuation of the baffle 35 and which is pivotally mounted at one end by means of the shaft 37. A shaft 43 is connected to the opposite end of the screen or sieve 42 by means of the opposite ends 44 of the slats 38 which are looped around the shaft 43. A rack bar 45 is keyed to each end of the shaft 43 and depends downwardly therefrom within and adjacent the side walls of the casing 11. A shaft 46 extends transversely through the casing 11 and is journaled therein. Pinions 47 are keyed to the shaft 46 within and adjacent the side walls of the casing 11 to mesh with the rack bars 45 so that when the shaft 46 is turned, by any suitable means, not shown, the last mentioned end of the screen or sieve 42 will be raised or lowered to cause the screen or sieve 42 to swing on the shaft 37 as a pivot. The side walls of the casing 11 are provided with stops 48 for engaging the ends of the shaft 43 to prevent the sieve 42 from being swung upwardly to a position where it will contact the periphery of the beater 31.

A baffle member 49 is mounted on the underside of the partition 21 and extends from side to side of the casing 11. Baffle member 49 includes a curved hood portion 50 which is disposed concentric with a portion of the periphery of the beater 31 and an upwardly bowed baffle portion 51, which extends from the lower end of the hood portion 50 upwardly and toward the opening 23. The baffle member 49 and the screen or sieve 42 combine to form an opening 52 therebetween, for a purpose which will hereinafter be described.

The sides of the casing 11 between sections 15 and 16 are provided with corresponding longitudinally extending openings 53 which extend from a point beneath, and adjacent the shaft 46, to a point adjacent the outlet end 13 of the cas-

ing 11. As best seen in Figure 6, the sections 15 and 16 are provided with outwardly projecting flanges 53' along the top and bottom edges of the openings 53 and which are adapted to receive the channel shaped frames 54 which are mounted therein with their sides in engagement with the flanges 53' and with their base portions 55 aligned with the sides of the casing 11. Frames 54 are secured in the openings 53 by means of the fastenings 56 which extend through the flanges 53' and the sides of the channel members 54 to thereby detachably mount the frames in the casing 11.

Referring particularly to Figures 1 and 7, the frames 54 at their ends, adjacent the shaft 46, are provided with perpendicular plates 57 in which are mounted follower screws 58 for engaging bearings 59 for urging the bearings toward the inlet end of the casing 11. A shaft 60 has its ends journaled in the bearings 59 and extends through slots 61 in the base portions 55, which are disposed longitudinally thereof, so that movement of the follower screws 58 will move the shaft 60 longitudinally of the frames 54 and of the casing 11. A shaft 62 extends transversely through the casing 11 and through perpendicular slots 63 in the opposite ends of the frames 54. As best seen in Figure 8, the ends of the shaft 62 are journaled in bearing blocks 64 which are mounted to slide perpendicularly in the guide frames 65 which are disposed in the frames 54. Follower screws 66 having locking nuts 67 are mounted in threaded openings in the base portions of the guide frames 65, the bottom sides of the frames 54 and the lower flanges 53'. The bearing blocks 64 may be raised and lowered by adjusting the follower screws 66 for raising and lowering the shaft 62, for a purpose which will hereinafter become apparent.

As best seen in Figures 3 and 7, an endless conveyor 68 is trained over the shafts 60 and 62. It will be obvious that the conveyor 68 may be tensioned by adjusting the shaft 60 by means of the follower screws 58 while one end thereof may be raised or lowered by adjusting the blocks 64, as heretofore described. The endless conveyor 68 includes a belt 69 which extends substantially the width of the casing 11 and which is provided with a plurality of outwardly projecting tufts of bristles 70, which are disposed in spaced apart relationship relatively to each other to form longitudinal and transverse spaced rows of tufts in which the adjacent tufts are spaced from one another to provide a checkered formation, as best seen in Figure 4. The sides of the casing 11 are provided with inwardly projecting guard flanges 71 which extend along the edges of the conveyor 68 and which are disposed slightly thereabove, for a purpose which will hereinafter become apparent.

A shaft 72 extends transversely through the casing 11, in the sides of which it is journaled, and is disposed above and substantially in a vertical plane with the shaft 62. A plurality of corresponding circular blades 73 are keyed to the shaft 72, within the casing 11, in spaced apart relationship relatively to each other. Each of the circular blades 73 is provided with teeth 74 at its periphery which teeth are each curved in a clockwise direction, as seen in Figure 3. As best seen in Figure 5, the blades 73 are disposed to align with the longitudinal spaces between the longitudinal rows of tufts 70, and as best seen in Figure 3 a portion of the periphery of the blades 73 coincide with a portion of the periph-

ery of the endless conveyor 68. Substantially semi-circular guard flanges 75 extend inwardly from the sides of the casing 11 and are disposed adjacent to and coaxially with the blades 73. The guard strips 75 extend from above and adjacent the guard strips 71 upwardly and around the portion of the blades 73 which is remote to the outlet 13.

A shaft 76 extends transversely through and is journaled in the sides of the casing 11 above the horizontal plane of the shaft 72 and between the shaft 72 and the outlet passage 13. A rotary brush 77, comprising a hub 78 and a plurality of radially projecting rows of tufts 79, is keyed to the shaft 76 and extends from side to side of the casing 11. A portion of the periphery of the rotary brush 77 is disposed to contact a portion of the peripheries of the blades 73, for a purpose which will hereinafter become apparent. The brush 77 is partially enclosed by means of an arcuately shaped hood 80 which is secured at its ends to the sides of the casing 11 and which is disposed concentric with the periphery of the brush 77 to surround a substantial portion thereof, leaving that portion adjacent to the blades 73, exposed. A guard flange 81 is secured to the casing 11 and extends from side to side thereof and is disposed with its free edge adjacent to the peripheries of the blades 73 and beneath the brush 77, for a purpose which will hereinafter become apparent.

The bottom section 16 of the casing 11 is provided with an outlet passage 82, adjacent the outlet end 13 of the casing 11 and with an inclined bottom portion 83 which slopes from the opposite end of the casing 11 downwardly to the passage 82 and which is disposed beneath the baffle 35, sieve 42 and a portion of the endless conveyor 68. The outlet passage 82 is provided with an opening 84 in one side thereof and adjacent its lower, open end. A valve 85 is pivotally mounted in the upper end of the opening 84 by means of a shaft 86, to which it is keyed, and which is provided with an extension arm 87 which projects at an obtuse angle to the valve 85 and which forms a support for a weight 88 which is adjustably positioned thereon by means of a set screw 89 and which is adapted to normally hold the valve 85 in a closed position, as seen in Figure 3. Valve 85 is adapted to swing into the opening 84, when moved to an open position to engage a stop 90, secured to the outer side of the passage 82 and which extends into the opening 84. As best seen in Figure 2, the valve 85 in its open, dotted line position, is disposed with its lower free edge spaced from the lower edge of the opening 84 forming a space therebetween, for a purpose which will hereinafter be described.

Referring particularly to Figures 1, 2, 5 and 6, one end of the shaft 33 extends beyond the side of the casing 11 and is provided with a pulley 91 which is keyed thereto and over which is trained a belt 92 which is adapted to be driven by any suitable means, not shown, for turning the shaft 33 in a counterclockwise direction, as viewed in Figure 1. A sprocket wheel 93 is keyed to the shaft 33, adjacent its opposite end and on the opposite side of the casing 11, and is connected to a sprocket wheel 94 which is keyed to the same end of the shaft 29 by means of a chain 95 for revolving the shaft 29 in the same direction as the shaft 33. A second sprocket wheel 96 is keyed to the shaft 33 beyond the sprocket wheel 93 which is connected to a sprocket wheel 97, on the corresponding end of the shaft 76, by means

of a chain 98 for turning the shaft 76 in the same, counterclockwise direction. A gear wheel 99 is keyed to the shaft 76 beyond the sprocket wheel 97, as best seen in Figure 5, to mesh with a gear wheel 100, keyed to the shaft 72 for turning the shaft 72 in the opposite direction to the shaft 76, or in a clockwise direction. As best seen in Figures 1 and 2, the sprocket wheel 101 is keyed to the shaft 72 between the gear wheel 100 and the casing 11 and is connected to a sprocket wheel 102 on the corresponding end of the shaft 62 by means of a chain 103 for turning the shaft 62 in a clockwise direction to cause the endless conveyor 68 to move in a clockwise direction, as seen in Figure 3, with the shaft 60 being driven thereby and operating as an idler shaft.

Assuming that the outlet passage 13 is connected to the inlet or suction end of a cotton gin or cotton mill, not shown, the suction from the gin or mill will create a suction within the casing 11 for drawing cotton into the casing through the inlet 12, which is adapted to be connected to a source of supply of cotton for the gin or mill. Assuming the inlet passage 12 to be in a horizontal position, as seen in full lines in Figure 3, the cotton drawn into the casing will come in contact with the periphery of the screen drum 28, which is turning in a counterclockwise direction, and will be directed downwardly thereby and into the beater 31. The screen drum 28 will prevent the cotton from entering the passage 22 without shutting off the suction therein. The cotton will be directed centrifugally from the beater 31 against the serrated baffle 35 which will cooperate with the spikes or tines 34 to break up the cotton bolls and lint to separate the foreign matter therefrom. The cotton and foreign matter will be carried on by the beater 31 to the sieve or screen 42, where the corrugated surface thereof will further cooperate with the tines 34 to continue to break up the cotton bolls and cotton lint. The fine particles of foreign matter will sift through the sieve 42 onto the sloping bottom portion 83 from where it will be directed to the outlet passage 82. The remainder of the cotton and foreign matter, not shown, will be carried on along the screen or sieve 42 and through the opening 52, beyond the free end thereof. Assuming the valve 24 to be in an open position, the cotton which has been separated from the foreign matter, so that it is light and fluffy, will be drawn from the opening 52 upwardly into the passage 22 through its opening 23, by the suction therein, and will be drawn directly through the passage 22 and the outlet passage 13. The remainder of the cotton and the foreign matter, which is too heavy to be drawn upwardly by the suction in passage 22, will drop onto the endless conveyor 68 by means of which it will be carried toward the circular blades 73. The formation of the tufts 70 will permit the foreign matter to drop into and become lodged between the spaces between the tufts 70, which spaces are sufficient in size and depth to receive cotton burrs. The light and fluffy cotton, on the other hand, will be supported on top of the tufts of bristles 70 to be thereby contacted by the teeth 74 which will pick up the cotton to thereby separate it from the foreign matter. The cotton will be carried by the blades 73, in a clockwise direction therearound to be engaged by the tufts 79 of the brush 77, which is turning at a greater speed than the blades 73, due to the proportionate sizes of the gear wheels 99 and 100, so that substantially all of the cotton will be

wiped off of the teeth 74 by the brush 77 from where it will be drawn by suction into the outlet 13. Any cotton that might escape the brush 77 will be removed from the teeth 74 by means of the guard flange 81 and thereafter be drawn into the outlet 13. The hood 80 will prevent the cotton from being carried around by the brush 77. The guard flanges 71 and 75 prevent the cotton and foreign matter from passing between the endless conveyor 68 and the battery of blades 73, respectively, and the sides of the casing 11 downwardly to the bottom section 16.

One side of the casing 11 is preferably provided with a window 104, as best seen in Figure 3, by means of which the operation of the machine 10 may be observed.

The foreign matter lodged in the spaces between the tufts 70 will move beneath the blades 73 and as the conveyor portion in which the foreign matter is carried passes around the shaft 62 the tufts 70 will be spread apart to allow the foreign matter to drop into the section 16 and the outlet passage 82. The weight 88 normally retains the valve 85 in a closed position, as seen in Figure 3 to maintain the suction within the casing 11, and as a result thereof the foreign matter from the screen or sieve 42 and from the endless conveyor 68 will be lodged on the valve 85 from which it may be released by manually raising the arm 87. If desired, the valve 85 may be arranged to function automatically by adjusting or entirely removing the weight 88 so that when the cotton gin or mill to which the machine 10 is connected is not in operation the weight of the valve 85 will cause it to swing to an open position into the opening 84 to release the foreign matter from the passage 82. When suction is again resumed in the casing 11 the valve 85 will be drawn back to a closed position thereby and it is for this reason that the opening 84 is of sufficient size to leave a space below the free edge of the valve 85 to insure that the valve 85 will be actuated by the suction and closed.

Obviously, the valve 24 may be adjusted to a plurality of positions to vary the suction in the opening 23. The shaft 46, as heretofore described, may be turned to move the screen or sieve 42 toward and away from the periphery of the beater 31. By adjusting the set screws 58 shaft 60 is moved relatively to shaft 62 for varying the tension on the endless conveyor 68. By adjusting the follower screws 66 the shaft 62 can be moved toward and away from the blades 73 for adjusting one end of the conveyor 68 relatively thereto and for incidentally varying the tension of the conveyor.

By removing fastenings 18 and 56 the bottom section 16 can be detached from the top section 15 so that the parts within the casing 11 can be repaired, adjusted or replaced. By removing the shaft 37 the screen or sieve 42 may be readily removed for repair or replacement, which will be occasionally required due to the wear on the screen fabric 41. The baffle 35 is preferably made of relatively thick sheet metal so that it will not require replacement and is therefore permanently secured to the casing by the fastenings 36. If desired, the endless conveyor 68, shafts 60 and 62 on which it is mounted, and the frames 54 may be removed from the casing 11 without detaching the sections 15 and 16 by removing the fastenings 56 and the chain 103 after which the aforementioned parts may be slid transversely out of the frame.

Various modifications and changes in the con-

struction and arrangement of the parts forming the machine are contemplated and may obviously be resorted to as only a preferred embodiment thereof has been illustrated and described.

5 I claim as my invention:

1. A cotton cleaning machine having an inlet at one end and an outlet at its opposite end, means for supplying suction to the outlet end for drawing cotton through the machine, a beater adjacent the inlet end for receiving the cotton, a screen disposed beneath the beater and onto which the cotton is directed for separating fine dirt particles from the cotton and through which the fine particles can pass to a waste outlet of the machine, conveying means disposed beneath and adjacent one end of the screen for receiving the cotton propelled over said end by the beater, and means for picking the cotton off of the conveying means for removing the cotton therefrom and for directing the cotton to said outlet, said screen being formed of mesh wire fabric, longitudinal supporting slats disposed beneath said fabric, and transverse slats supported by said longitudinal slats and arranged in spaced apart relationship beneath the mesh wire fabric to provide an undulating or corrugated screen surface.

2. A cotton cleaning machine comprising a casing having an inlet at one end and an outlet at its opposite end, means for supplying suction to the outlet end for drawing cotton through the machine, a beater adjacent the inlet end for receiving the cotton, a screen disposed beneath the beater and onto which the cotton is directed for separating fine dirt particles from the cotton and through which the fine particles can pass to a waste outlet of the machine, conveying means disposed beneath and adjacent one end of the screen for receiving the cotton propelled over said end by the beater, and means for picking the cotton off of the conveying means for removing the cotton therefrom and for directing the cotton to said outlet, comprising a passage formed in the top of said casing and extending from adjacent the inlet end thereof to adjacent its outlet end, a screen drum mounted in the casing between its inlet end and the adjacent end of said passage to prevent the cotton from passing from said inlet end directly into the passage, said passage having an opening intermediate of its ends communicating with the main portion of the casing for receiving a portion of the cotton, directly from the beater for conveying said cotton directly to the outlet end of the casing.

3. A cotton cleaning machine comprising a casing having an inlet at one end and an outlet at its opposite end, means for supplying suction to the outlet end for drawing cotton through the machine, a beater adjacent the inlet and for receiving the cotton, a screen disposed beneath the beater and onto which the cotton is directed for separating fine dirt particles from the cotton and through which the fine particles can pass to a waste outlet of the machine, conveying means disposed beneath and adjacent one end of the screen for receiving the cotton propelled over said end by the beater, and means for picking the cotton off of the conveying means for removing the cotton therefrom and for directing the cotton to said outlet, comprising a passage formed in the top of said casing and extending from adjacent the inlet end thereof to adjacent its outlet end, a screen drum mounted in the casing between its inlet end and the ad-

adjacent end of said passage to prevent the cotton from passing from said inlet end directly into the passage, said passage having an opening intermediate of its ends communicating with the main portion of the casing for receiving a portion of the cotton, directly from the beater for conveying said cotton directly to the outlet end of the casing, a closure for said opening, and rack and pinion means for adjustably positioning said closure.

4. A cotton cleaning machine having an inlet at one end for cotton to be cleaned, a beater adjacent said inlet end for breaking up the cotton, a concave screen over which the cotton is propelled by said beater for separating the fine particles of dirt from the cotton, conveyor means for receiving the cotton and larger pieces of foreign matter, associated therewith, propelled off of an end of the screen by the beater, means for removing the cotton from said conveyor, an outlet disposed adjacent said last mentioned means for receiving the cotton therefrom, the outlet end of said casing being connected to the suction end of a gin or cotton mill for creating a suction within the casing, a passage extending through the upper portion of the casing from adjacent its inlet end to adjacent its outlet end, a mesh wire fabric screen covering the end of said passage disposed adjacent the inlet end of the casing to prevent the cotton from passing therethrough, and said passage having an opening intermediate of its ends communicating with the interior of said casing for receiving the lint cotton from the beater for conveying it directly to the outlet end of the casing.

5. A cotton cleaning machine having an inlet at one end for cotton to be cleaned, a beater adjacent said inlet end for breaking up the cotton, a concave screen over which the cotton is propelled by said beater for separating the fine particles of dirt from the cotton, conveyor means for receiving the cotton and larger pieces of foreign matter, associated therewith, propelled off of an end of the screen by the beater, means for removing the cotton from said conveyor, an outlet disposed adjacent said last mentioned means for receiving the cotton therefrom, and a concave corrugated baffle member disposed adjacent the periphery of the beater for receiving cotton, hurled centrifugally therefrom for breaking up the cotton to separate the foreign particles therefrom, said concave screen having one end connected to an end of said baffle to receive the cotton and foreign particles from the baffle whereby fine particles of foreign matter may pass through the screen and be separated from the cotton and the larger particles of foreign matter.

6. A cotton cleaning machine comprising a casing having an inlet at one end thereof and an outlet adjacent its opposite end for connecting with a cotton gin or cotton mill for creating a suction within the casing, a passage formed in the top of said casing and extending from adjacent its inlet end to adjacent its outlet end, a mesh wire fabric drum rotatably mounted in the casing between the inlet end and the adjacent end of said passage for preventing the cotton from passing from said inlet end into the passage and for directing the cotton downwardly, a rotary beater disposed beneath the drum for receiving the cotton, an arcuately shaped corrugated baffle mounted in said casing and disposed adjacent a portion of the periphery of

the beater to receive the cotton directed centrifugally from the beater to cooperate therewith in breaking up the cotton, an arcuately shaped sieve member disposed adjacent a portion of the periphery of the beater to form a continuation of said baffle for separating the fine particles of foreign matter from the cotton in passing thereover, an opening in said passage, communicating with the lower portion of the casing and disposed adjacent the beater to receive cotton, separated from the foreign matter for conveying it directly to the casing outlet, conveyor means disposed beneath one end of said sieve for receiving and conveying the cotton containing larger particles of foreign matter, and means for removing the cotton from the conveyor for separating it from the foreign particles carried thereby for directing the cotton to the casing outlet.

20 7. A machine as in claim 6, comprising an outlet in the bottom of said casing for receiving the foreign matter from the sieve and conveyor for discharging it from the casing, and a normally closed valve for closing said outlet for maintaining the suction in the casing.

8. A cotton cleaning machine comprising a casing through which cotton is adapted to be conveyed by suction, a beater to receive the cotton entering the casing, a screen over which the cotton is propelled by the beater for agitating the cotton to separate the fine particles of foreign matter therefrom so that the foreign matter can be separated from the cotton by passing through the screen, said screen extending from one end of the casing to a point intermediate of its ends, a passage having an inlet above and adjacent the last mentioned free end of the screen for receiving the light, clean cotton therefrom and for conveying it directly to the casing's outlet, an endless conveyor, extending from beneath the free end of the screen to the opposite end of the casing, for receiving the larger particles of foreign matter and the cotton attached thereto, said endless conveyor having means for separating the foreign matter from the cotton, and means for removing the cotton from the conveyor and for directing it toward the outlet of the casing.

9. A cotton cleaning machine having an inlet at one end and an outlet at its opposite end, means for supplying suction to the outlet end for drawing cotton through the machine, a beater adjacent the inlet end for receiving the cotton, a screen disposed beneath the beater and onto which the cotton is directed for separating fine dirt particles from the cotton and through which the fine particles can pass to a waste outlet of the machine, said screen being secured to the inlet end of the machine and having a free end disposed intermediate of the inlet and outlet ends of the machine, conveying means extending from adjacent the outlet end of the machine to the free end of the screen for receiving the cotton propelled over said free end by the beater, and means for picking the cotton off of the conveying means for removing the cotton therefrom and for directing the cotton to said outlet, said machine having a clear unobstructed passage between the free end of the screen and said last mentioned means, said conveyor means comprising an endless belt provided with outwardly projecting tufts arranged in longitudinal and transverse spaced rows.

JOHN T. LAWRENCE.
